ASSIGNORS, BY MESNE ASSIGNMENTS, TO SECOND NATIONAL BANK OF
BALTIMORE, TRUSTEE, OF BALTIMORE, MARYLAND.

DESIGN FOR A PORTABLE ELECTRIC VALVE-GRINDER.

57,577.

Specification for Design. Patented Apr. 26, 1921.

Application filed May 17, 1920. Serial No. 382,171. Term of patent 14 years.

To all whom it may concern:

Be it known that we, SAMUEL DUNCAN BLACK and ALONZO G. DECKER, citizens of the United States of America, and residents of Towson, county of Baltimore, State of Maryland, have invented a new, original, and ornamental Design for a Portable Electric Valve-Grinder, of which the following is a specification.

In the accompanying drawing we have illustrated a portable electric valve grinder, constructed in accordance with our invention.

The figure is a perspective view of the same.

The device as seen consists of a hexagonal motor casing, 1, a gear casing, 2, a switch-

box, 3, a grip, 4, like the grip of a pistol, and a trigger-like controlling switch adjacent the grip, in the relation borne by a pistol trigger to the grip or butt.

Having thus described and illustrated our invention, we claim:

The ornamental design for a portable electric valve grinder, substantially as shown and described.

Signed by us at Towson, Maryland, this 6th day of May, 1920.

SAMUEL DUNCAN BLACK.
ALONZO G. DECKER.
